Primary Examiner — Cynthia Ramirez*Assistant Examiner* — Gino Colan(74) *Attorney, Agent, or Firm* — The Reilly Intellectual Property Law Firm, P.C.(57) **CLAIM**

The ornamental design for a particle collector, as shown and described.

DESCRIPTION

FIG. 1 is a perspective view of a particle collector showing our new design;

FIG. 2 is a top plan view of FIG. 1;

FIG. 3 is a side view of FIG. 1;

FIG. 4 is a bottom plan view of FIG. 1;

FIG. 5 is another side view of FIG. 1;

FIG. 6 is another side view of FIG. 1;

FIG. 7 is another side view of FIG. 1; and,

FIG. 8 is an exploded view of FIG. 1.
